METHOD OF PRODUCING A FOOD PRODUCT
FROM SCRAP PARTICLES OF HIDEDavid Torr, New York, N. Y., assignor to
Charles J. Ely, Oakland, N. J.No Drawing. Application December 23, 1950,
Serial No. 202,581

2 Claims. (Cl. 260—118)

1

This invention relates to hide and has for its object the conversion of hides into a colloidal state. The invention provides an improved process for converting waste particles such as trimmings and scraps of hide into a colloidal state, and the products resulting from the improved process.

In the meat packing plants there is a large volume of hide scraps which are processed for the production of glue and gelatin. Glue and gelatin are very much alike chemically and physically. High grade glues are similar to gelatins and chemically both glue and gelatin are proteins. Hides and their connective tissues are important sources of collagen, a water-insoluble substance which is the mother substance of glue and gelatin. On boiling of the hides and tissue in water, the collagen breaks down by decomposition or hydrolysis to form glue or gelatin.

In accordance with the process of my invention, the scraps of hide are reduced to a suitable degree of subdivision in a preliminary operation as in a hammer mill or shredder. Usually the green hide contains enough water for the subsequent operation of disintegrating and dispersing to form a colloidal product.

The hide, after having been subdivided in the preliminary treatment, is passed through a colloidizing operation, preferably in at least two stages of colloidal disintegration in colloidal mills. It is usually advantageous to pass the material through an initial colloid mill in which the clearance between the stator and rotor is from 0.001 to 0.010 inch and then through a final mill in which the clearance is practically zero, the stator and rotor being in vertical contact. A Premier mill having a conical rotor of $\frac{1}{4}$ inch diameter and rotated on a vertical shaft at from 12,000 to 15,000 R. P. M. gives effective results in the final stage. I prefer to use mills having rotors and stators formed of a material such as Carborundum, synthetic sapphires, or diamonds, which have irregular surfaces, the dispersed mass being forced through the intervening tortuous passages between the crystal projections of the materials. The particles of the finished colloidal mass are reduced to such a state of fineness that they are in general below 10 microns and advantageously below 5 microns.

In the final stage a considerable amount of heat is generated and cooling may be necessary to avoid overheating of the material during disintegration. By proper regulations of the temperature during the disintegration in the colloid mill, the product may be heated as required.

2

The disintegrating operation is advantageously carried out in an inert atmosphere, such as nitrogen or carbon dioxide, or with protection of the material from the air to avoid oxidation. 5 The colloid mill is thus advantageously provided with an enclosed hood or cover and with feed and discharge passages provided with protective covering so that the material is protected from air oxidation. Depending on the final product 10 desired the temperature in the colloid mill may range from near freezing up to near the boiling point of water.

The heating of the material during disintegration may tend to remove more or less water therefrom and to dry out the product. This can be avoided, and a product of increased moisture content obtained when desired by admixing water with the product before or during the final disintegration to give a final product of a regulated 15 and predetermined moisture content. Where the moisture content is around 15 to 30% the feed to the mill is advantageously a forced feed. With higher moisture content of the material, e. g., between 50 and 60%, or up to 100% or even 20 25 200 or 300 or 500% or higher based on the solid content (dry basis) the gravity feed may be sufficient.

In the foregoing description of my method of producing a colloidal product, I have referred 30 to the use of a colloid mill. A similar product, or a product of even finer particle size, can be obtained by utilizing ultrasonic equipment, or by bombardment of the particles by X-rays, ultraviolet rays, ionic rays, atomic rays and electronic bombardment or disintegration, or bombardment with gases, as in micronizing equipment, for the disintegration or for further disintegration of both the inorganic and organic components.

35 The colloidal operation carried out on the hides breaks down the tissues into such minute particles that the substances imprisoned in the cellular structure are exposed and made more readily available for extraction or assimilation. The 40 relatively large molecules of the protein collagen appear to be broken down or hydrolyzed into glue, gelatin, or both. My invention, accordingly, provides an efficient process for the conversion of constituents of the hide into glue or gelatin which may be easily recovered from the colloidal product for use as end products.

The colloidal products of the invention may be used to form various products such as coatings, sheets, and molded articles. They may be 45 admixed with plastics, fillers or binders to form

modified products for similar purposes. Sheets may be formed as a substitute for leather or as a synthetic leather. Coatings of various kinds may be produced from the colloidal products which are advantageously useful for application to paper and textiles.

If the hide scraps have been handled with such care as to permit their use as food, then the colloidal hide product is useful as a food. It may be used directly as a liquid food high in 10 easily assimilable protein or be blended with other colloidal vegetable or animal products. For example, my colloidal hide product may be blended with the colloidal bone product of my application Serial No. 159,857, filed May 3, 1950, now Patent No. 2,622,027, or the colloidal egg product of my application Serial No. 201,693, filed December 19, 1950. The colloidal hide product may be added 15 to soups, purees, and to vegetable or meat products, advantageously those preserved in cans or frozen packages, to obtain an enriched or better balanced food. The invention accordingly contemplates the provision of canned or packaged products of the invention as directly produced or 20 as blends or admixtures with other foods.

I claim:

1. The method of treating scrap particles of hide which comprises reducing the hide to a state of colloidal dispersion in a colloidizing operation, producing a product having the Brownian movement, the particles being less than 10 microns, the colloidizing operation being carried out at a temperature which hydrolyzes protein of the hide into gelatin.

2. The method of treating scrap particles of hide which comprises reducing the hide to a state of colloidal dispersion in a colloidizing operation, producing a product having the Brownian movement, the particles being less than 10 microns, said operation reducing the collagen to glue and gelatin, and extracting the glue and gelatin from the product.
